URI D. FOSTER, OF HARTFORD, CONNECTICUT, ASSIGNOR TO THE HART & HEGERMAN MANUFACTURING COMPANY, OF HARTFORD, CONNECTICUT, A CORPORATION OF CONNECTICUT.

METAL-WORKING MACHINE.

Application filed January 13, 1922. Serial No. 528,926.

To all whom it may concern:

Be it known that I, Uri D. Foster, a citizen of the United States, residing at Hartford, in the county of Hartford and State of Connecticut, have invented certain new and useful Improvements in Metal-Working Machines, of which the following is a specification.

This invention relates to a metal-working machine. The principal object of the invention is to provide means of a highly effective nature, for at once automatically stopping the machine in case an obstruction is met. While the invention is capable of advantageous incorporation in machines of several different kinds, it is however, of peculiar utility when embodied in a machine for tapping, the machine being at once stopped in case the stock is not properly presented for action by the tap or equivalent implement.

In the drawings accompanying and forming part of the present specification I have shown rather fully one of the several forms of embodiment of the invention, which to enable those skilled in the art to practice the invention will be set forth fully in the following description. Clearly I am not restricted to this disclosure. I may depart therefrom in several respects within the scope of the invention defined by the claims following said description.

Referring to said drawings:

Figure 1 is a top plan view of a machine involving the invention.

Figs. 2 and 3 are opposite side elevations of the machine as seen for example from the right and left.

Like characters refer to like parts throughout the several views.

The different parts of the machine may be carried in any convenient manner, the base or bed 2 being generally provided for the purpose and comprising ordinarily, a practically rectangular plate. The work support may be of any suitable kind; that shown is denoted by 3 and it is sustained upon the upper side of the base or bed 2 near an end thereof. As shown it is provided with lateral lugs or ears 4 longitudinally slotted to receive the screws 5, which are tapped into the base or bed 2. This construction provides for a rotary adjustment when necessary, of the work support 3, the

latter being held normally in rigid relation by the heads of the screws 5 which bind against the lugs 4. The work support 3 presents a convenient means for sustaining what may be considered as a work carrier, which I will hereinafter describe, but which I might note at this point is practically in the form of a slotted table 6, rotative upon the work support 3 and hereinafter with its adjuncts, more fully set forth.

The tool mechanism may be carried in any convenient way, the tool support 7 being shown for the purpose and generally consisting of a vertically disposed plate rigid with the base or bed 2 and rising therefrom.

The tool 8 shown is a tap although it may be not always necessary to utilize it. As illustrated it is removably held in the chuck 9 (Fig. 3) rigid with the lower end of the spindle 10, the tool support 7 having superposed bearings or arms 11 to rotatively receive the spindle 10. The spindle 10 which is of compound construction as I will hereinafter more particularly set forth, in addition to being rotative, is given an endwise or longitudinal movement and this may be secured by threading as at 12, the upper section of the spindle, to extend through the nut 13 rigid with the support or bearing 7, so that when the spindle 10 is rotated it is at the same time moved endwise. The spindle as noted, is in two sections. The sections are connected by a coupling 10' pivoted as at 12' to the upper section and loosely connected as at 10'' with the lower section of the spindle, so that should the lower section of the spindle meet an obstruction, its lower section can yield backwardly, without causing any trouble.

As shown the upper section of the spindle 10 has rigid with it the pinion 14, in mesh with the spur gear 15. The spur gear 15, as shown is rigid with the shaft 16, which has rigid with it the bevel pinion 17, in mesh with the lateral teeth of the gear member 18, shown as a segment. The segment 18 is sustained for rocking movement upon the support 7. The main shaft is designated by 19 and as shown, is sustained for rotary movement upon the upper rear corner of the support 7. Said shaft 19 has rigidly connected with it a crank arm 20, to the outer end of which is jointed, as by pivoting,

the link 21 which is likewise united with the segment 18 between the ends thereof, so that when the shaft turns, the crank arm 20 turns with it, and through the link 21 5 rocks the segment 18.

The work to be acted upon may be of any desired kind and the tool may vary, although as I have hereinbefore set forth, a tap as 8 is shown. The work support is denoted 10 by 3 although strictly speaking the work is not directly carried thereby but rather by an index plate such as the disk 6 which has in its periphery notches 23, thus providing therebetween the peripheral teeth 24. 15 The index plate or disk 6 is given an intermittent movement so as to successfully position the work for action by the tool 8. For the purpose described the plate or disk 6 may have through it the slots or openings 20 25 spaced predetermined distances apart.

The intermittent or step-by-step movement of the plate or disk 26 is accomplished through the agency of a pawl 27. The pawl 27 as shown, is connected for longitudinal 25 adjustment as by screws 28, adapted, to interchangably enter a longitudinal row of perforations 29 in the pawl, and to be tapped into studs 30 rigid with and rising from the pawl-carrier 31, below the pawl, and the 30 rear end of which is perforated to receive the pivot 32, on which the pawl-carrier 31 and the pawl rigid therewith, can turn. The pawl 27 is held in yielding contact with the disk 6 by the spring arm 33 rigidly connected as by the screw 34, with the pivot 32. The pivot 32 as shown extends downwardly through a longitudinal slot 35 at the forward end of the bar 36 and is held in 35 adjusted position with respect to the bar as by the nut 37.

The bar or slide 36 is power-operated in one direction and spring-operated in the other direction, the means shown for this purpose will now be set forth. To the tail 45 end of said bar or slide 36 is jointed the lower branch or arm of the lever 38 pivoted between its ends to the support or column 7. The upper branch of the lever having a stud 39, engageable by a cam 40 rigid with the shaft 19 and to rotate therewith, so that as the shaft turns the lever 38 will be rocked to impart endwise or longitudinal movement to the bar or slide 36. This is the normal action of the machine. When however the 50 lever 38 and the bar 36 are thrown out of action, it follows that the index plate or disk 6 will not be rotated, nor will the spindle 10 be rotated as will be hereinafter explained.

There is pinned or otherwise suitably fastened, to the shaft 42 a driver such as the cone pulley 43, illustrated as having three steps and which may be operated from some suitable source of power. The shaft 42 also 55 has loose on it a pinion 44 in mesh with the

spur gear 45 loose on the shaft 19. There is rigid with shaft 19 the disk or plate 46, shown as pivotally carrying the pawl or dog 47, which coacts with the collar 48, rigid with the gear 45 and loose on said shaft 19 70 and having a peripheral notch or slot 49 to receive the tooth 50 of the pawl 47. The disk, wheel or plate 46 and the pawl 47 constitute one member of a clutch, the complementary member being constituted by the collar 48. The tooth 50 of the pawl 47 is normally held in the notch or slot 49 by the spring 51, connected therewith and also connected with the disk or wheel 46. 75

The shaft 42 as shown, pivotally supports between its ends the latch 52, the free end of the upper branch of which is adapted to engage under the toe of the pawl or dog 47 to disengage the pawl or dog from the clutch member or disk 46. To the lower branch of the latch 52 is connected one end of the coiled pull-spring 53, the opposite terminal thereof being connected with the base or bed 2. Said spring under normal action, holds the upper end of the latch 52 80 in the path of the pawl or dog 47, under the toe of this pawl 47 and against the periphery of the wheel 46. The latch 52 however during the normal action of the machine is tripped on each backward movement of the bar or slide 36, so as to prevent unclutching. For the purpose of tripping, the latch, a tripper or actuator as 54 is shown, being adjustable and represented as in the form 85 of a screw, threaded through the collar 55, rigid on the bar of slide 36. After the bar or slide is retracted the tripper or actuator 54, strikes the lower arm of the latch 52 and carries the top or upper end thereof 90 from out of the path of the pawl or dog 47. Should the bar or slide 36 remain in its forward position there will be nothing to trip the latch 52 and as a consequence it is caused by the spring 53 to remain in such position 95 as to be engaged by the free end of the pawl or dog 47 as the disk or wheel 46 rotates, thus carrying the tooth 50 out of the notch 49 and permitting the collar 48 and gear 45 to rotate freely on the shaft 19 and in consequence allow all other parts of the machine to remain at rest. 100

The slide or bar 36 as shown is supported by the bearings 56 and 57, rigid with the support 7, the rear bearing 57 functioning as a stop to limit the rearward movement of the slide or bar 36. The collar 55 adjustable on the bar 36 is provided to retard the rearward movement of said bar, this being necessary to compensate for variations in the sizes of the articles to be tapped. In the illustration given, the disk 6 is intermittently rotated, the amount of each step or intermittent movement being governed by the bar 36, the rearward movement of which is effected by the spring 59 and the forward 115 120 125 130

movement of which is positively effected through the action of the lever 58, acted on by the cam 48.

What I claim is:—

- 5 1. A machine of the class described comprising a power-driving member, a driven member to co-operate with the driving member, a work-carrier, an actuator for the work carrier operable in one direction by 10 the driven member, independent means for imparting opposite movement to the actuator, a clutching means between the driving and the driven members, and means for operating the clutching means to throw the 15 driving and the driven members out of working relation in case the actuator should not complete its movement.

2. A machine of the class described comprising a power-driving member, a driven member to co-operate with the driving member, a work-carrier, a clutching member between the driving and the driven members and acting normally to automatically couple the same, a work carrier, a reciprocatory actuator operable by the driven member, a latch to engage the clutching member, and means associated with the actuator for tripping the latch on each complete movement of the actuator to thus permit the clutching member to couple the driving and the driven members on each said complete movement.

3. A machine of the class described comprising a power-driving member, a driven member to co-operate with the driving member, a work-carrier, a clutching member between the driving and the driven members, spring means acting to automatically normally cause the clutching member to 40 couple the driving and the driven members, a work carrier, a reciprocatory actuator operable by the driven member, a latch to engage the clutching member, and means associated with the actuator for tripping the 45 latch on each complete movement of the actuator to thus permit the clutching member to couple the driving and the driven members on each said complete movement.

4. A machine of the class described comprising a power-driving member, a driven member to co-operate with the driving member, a work-carrier, a clutching member between the driving and the driven members and acting normally to automatically couple the same, a work carrier, a reciprocatory actuator operable by the driven member, a latch to engage the clutching member and adjustable means associated with the actuator, for tripping the latch 55 on each complete movement of the actuator to thus permit the clutching member to couple the driving and the driven members on each complete movement.

5. A machine of the class described comprising a power driving member, a driven

member to co-operate with the driving member, a work-carrier, a pawl pivoted upon the driving member, a spring for urging the pawl toward and into coupling relation with the driven member, a reciprocatory bar, 70 means actuated by the driven member, for advancing said reciprocatory bar, said reciprocatory bar having means associated therewith for causing the movement of the work carrier, spring means for effecting the 75 return movement to the reciprocatory bar, a latch, means for moving the latch under said pawl, the reciprocatory bar having means to trip the latch on each backward movement thereof.

6. A machine of the class described comprising a power-driving member, a driven member to co-operate with the driving member, a work-carrier, a pawl pivoted upon the driving member, and automatically movable into 85 coupling relation with the driven member, a reciprocatory bar, means actuated by the driven member, for advancing said reciprocatory bar, said reciprocatory bar having means associated therewith for causing the 90 movement of the work carrier, spring means for effecting the return of the reciprocatory bar, a latch, means for moving the latch under said pawl, the reciprocatory bar having means to trip the latch on each back- 95 ward movement thereof.

7. A machine of the class described comprising a power-driving member, a driven member to co-operate with the driving member, a toothed work carrier, a pawl 100 pivoted upon the driving member, and automatically movable into coupling relation with the driven member, a reciprocatory bar, means actuated by the driven member, for advancing said reciprocatory bar, said 105 reciprocatory bar having a pawl for engaging the teeth of the work carrier for rotating the same, means for effecting the return movement to the reciprocatory bar, a latch and means for moving the latch under 110 said first pawl, the reciprocatory bar having means to trip the latch on each backward movement thereof.

8. A machine of the class described comprising a power-driving member, a driven member to co-operate with the driving member, a peripherally toothed work-carrier, a pawl pivoted upon the driving member and automatically movable into coupling relation with the driven member, a reciprocatory bar, means for reciprocating 120 said bar, the latter having a pawl for engaging the teeth of the work carrier for rotating the same, a latch, and means for moving the latch under said first pawl, the reciprocatory bar having means to trip the latch on each backward movement thereof.

9. A machine of the class described comprising a power-driving member, a driven member to co-operate with the driving member, a 130

work carrier, a pawl pivoted upon the driving member and automatically movable into coupling relation with the driven member, a reciprocatory bar, means actuated by the
5 driven member, for advancing said reciprocatory bar, the latter having means for causing the rotation intermittently of the work carrier, independent means for effecting the return movement of the reciprocatory bar, a latch, and a collar on the re-

ciprocatory bar having a screw threaded therethrough, for moving the latch under the pawl on each backward movement of the reciprocatory member.

In testimony whereof I affix my signature.

URI D. FOSTER.
